HAT PROTECTOR

Max H. Friedler, Lewiston, Maine

Application May 17, 1935, Serial No. 22,033

6 Claims. (Cl. 206—8)

This invention relates to a hat protector particularly adapted for use by cleaners and haberdasheries and retail stores who sell men's felt or soft hats.

5 An object of the invention is to provide a hat protector which will protect the brim and crown from dust. Another object is to provide a hat protector which can be manufactured at a small cost and which is simple in detail so that it may 10 be quickly and easily placed on the hat.

Another object of the invention is to provide a hat protector which will more or less yieldably support or hold a hat so that when the protector is inserted into a shopping bag or box, it will prevent the hat or edges of the brim from coming 15 in contact with the edge of the paper or box.

Another object of the invention is to provide a hat protector which can be manufactured cheaply and upon which a hat may be easily placed so that the protector will keep the hat 20 away from the shelf or other object upon which it is placed.

Other objects and advantages of the invention 25 will become apparent during the course of the following description.

The essential characteristics will be summarized in the claims.

30 Referring to the drawing, Fig. 1 is a plan view of the base of my hat protector. Fig. 2 is a plan view of the crown protector as cut. Fig. 3 shows an end view of the base section with the crown section attached thereto and Fig. 4 shows a side view partially cut away showing the base section and the manner in which the securing members are inserted in the sweat band of the 35 hat. Fig. 4 is on a slightly enlarged scale.

40 Referring again to the drawings in Fig. 1, the numeral 10, indicates the base of my hat protector preferably formed by a single sheet of cardboard or similar material of sufficient thickness to support a hat. This sheet may be of any length or width, but a convenient size is found to be approximately twelve (12) inches wide by 45 fifteen (15) inches long. The dotted lines 11 and 12 are slightly scored to help in bending the ends. The base section has two slots cut through as indicated by the lines 16 and 17 respectively. In the center our base member 10 is cut through 50 along lines 20, 21 and 23 to form securing members 27 and 28 respectively. The securing members being integral with base member 10 along dotted lines 24 and 25 respectively which are 55 slightly scored, so that said securing members

member 10. These securing members 27 and 28 each have two irregular slots, 29 and 30 on securing member 27; and 31 and 32 on securing member 28. Securing member 27 is also slightly scored along dotted lines 33 and 34 and securing member 28 is slightly scored along lines 35 and 36 to assist in placing said members in the hat. The numeral 40 indicates the crown protector formed by a flat piece of cardboard or other suitable material and preferably of oblong shape 10 as shown in Fig. 2. This crown protector 40 has 2 arms 41 and 42 which are cut through with exception of the dotted lines 43, and 44 respectively, which are slightly scored. Said arms are also slightly scored along dotted lines 37 and 38 15 respectively. One end of the crown protector 40 is provided with a locking member 45 which is adapted to engage a slot 46 on the opposite end.

20 In Fig. 4, I show an ordinary soft felt hat 47 in place on my hat protector 10. This view as 25 broken away quite clearly shows how the securing member 28 holds the hat against lateral displacement on the hat protector. This is simply done by placing the sweat-band 48 of the hat into slots 32 and 31 on the one side, and 29 and 30 on the other so that a part of the securing member 28 contacts the sweat-band between the 30 band and the felt hat and another part of the securing member contacts the sweat-band on the side which comes in contact with the wearer's head. Fig. 4 also more clearly shows the arms 41 and 42 of the crown protector as they enter slots 16 and 17 respectively, thus holding the ends of base member 10 substantially perpendicular to the base, to partially protect the brim 35 of the hat, and also adapted to secure the crown member to the base member.

40 The easiest method to assemble the units is as follows: take the crown member 40, place the locking member 45 in the slot 46, thus forming a circular band. Place the hat bottom-side up with the crown within the circular band of the crown protector. Next take the base member 10 and place it on the top of the hat brim. Bend the securing members 27 and 28 at right angles with the base member and down into the inside of the hat, placing the sweat-band in slots 29, 30, 31 and 32 as shown by band within slot 32 in Fig. 4. This will hold the hat with reference to 50 any movement on base member 10. Next take the arms 41 and 42 and place them into the slots formed by lines 16, 17 respectively. This secures the crown member to the base member. Thus it is obvious that the hat 47 is securely held on the 55

base member 10 and prevented from lateral displacement in any direction, thus protecting the brim from coming in contact with any container in which the hat and hat protector may be placed.

It is also obvious that the bottom of the brim is protected from the dust on any shelf or object on which the hat protector may be placed, and the crown is protected from being squashed by any object which might come in contact with it.

Obviously the base member 10 can be made in any shape, and I only show it in a rectangle shape as a preferred example of the invention.

15 The preferred material which I use for both the base member 10 and the crown member 40 is made of cardboard of suitable strength and rigidity to hold a hat. Of course other materials may be used such as leather, bristol board, press board, or pulp products or the like. The process of manufacture is extremely simple since both the base member and the brim member may be punched and scored by one single operation and from one piece of material with a very little waste.

30 I believe that I have provided a hat protector which can be easily and cheaply manufactured, which can be assembled in a very few minutes, and which is of great use in protecting a hat after it has been cleansed and blocked or in shipping, retailing or storing hats in the general course of business.

What I claim as new is as follows:

35 1. A hat protector comprising a base member having a plurality of securing members integral therewith, said securing members being adapted to bend at right angles with said base member and having a plurality of slots therein, said slots dividing the securing member into two parts, one part being adapted to contact the inside of a sweat band, and the other part being adapted to contact the outside of a sweat band to thus hold the hat from lateral displacement with reference to the hat protector.

40 2. A hat protector comprising a base member having two securing members integral therewith, said securing members being divided into two

parts, one part being adapted to contact the inside of a sweat band and the other part being adapted to contact the outside of the sweat band, which parts of the securing members coact with the base member to hold the hat against lateral displacement with reference to the said base member.

45 3. A hat protector comprising a base member, a plurality of securing members integral with the base member having slots therein partially separating said securing members into two sections, one section being adapted to contact the inside of the sweat band, the other section being adapted to contact the outside of the sweat band, a crown member adapted to enclose the crown of 15 the hat and means securing the crown member to the base member.

4. A hat protector comprising a base member, two securing members integral with the base member and adapted to bend at right angles 20 with said member, each of said securing members having two slots therein, separating each securing member into four sections, two of said sections being adapted to contact the inside of a sweat band the other two sections being adapted 25 to contact the outside of a sweat band, which sections coact with the base member to hold the hat against lateral displacement with reference to the base member.

5. A hat protector comprising a base member 30 having two securing members integral therewith said securing members being separated into a plurality of parts one or more of said parts being adapted to contact the outside of the sweat band, one or more of said parts being adapted to contact the upper edge and inside of the sweat band, which said parts coact with the base member, to hold the hat against lateral displacement with reference to said base member.

45 6. A hat protector comprising a base member, 40 a plurality of securing members integral therewith and means associated with the securing members for clasping a sweat band to thus prevent lateral displacement of the hat with reference to the base member.

MAX H. FRIEGLER.
